(57) **CLAIM**

The ornamental design for a vehicle side window curtain, as shown and described.

DESCRIPTION

FIG. 1 is a front elevational view of a curtain embodying my design, the broken lines demonstrating stiches;
FIG. 2 is a rear elevational view thereof;
FIG. 3 is a right side elevational view thereof;
FIG. 4 is a left side elevational view thereof;
FIG. 5 is a top plan view thereof;
FIG. 6 is a bottom plan view thereof;
FIG. 7 is a front elevational view of a second embodiment of my design;
FIG. 8 is a rear elevational view thereof;
FIG. 9 is a right side elevational view thereof;
FIG. 10 is a left side elevational view thereof;
FIG. 11 is a top plan view thereof;
FIG. 12 is a bottom plan view thereof;
FIG. 13 is a front elevational view of a third embodiment of my design;
FIG. 14 is a rear elevational view thereof;
FIG. 15 is a right side elevational view thereof;
FIG. 16 is a left side elevational view thereof;
FIG. 17 is a top plan view thereof; and,
FIG. 18 is a bottom plan view thereof.
